US0D1057174S

(12) **United States Design Patent** (10) Patent No.: **US D1,057,174 S**
(45) Date of Patent: ** Jan. 7, 2025

(54) **TOUCH INTERFACE DEVICE**

(71) Applicant: **A-DEC, INC.**, Newberg, OR (US)

(72) Inventors: **Jason Joel Alvarez**, Portland, OR (US);
Michael John Irving, Tigard, OR (US);
Matthew Douglas Borden, Beaverton,
OR (US)

(73) Assignee: **A-DEC, INC.**, Newberg, OR (US)

(**) Term: **15 Years**

(21) Appl. No.: **29/872,456**

(22) Filed: **Mar. 13, 2023**

(51) LOC (15) Cl. **24-02**

(52) U.S. Cl.

USPC **D24/185**

CLAIM

The ornamental design for a touch interface device, as shown and described.

DESCRIPTION

FIG. 1 is a front perspective view of a touch interface device, showing our design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines depict portions of the touch interface device that form no part of the claimed design.

1 Claim, 7 Drawing Sheets
